2 Sheets-Sheet 2

UNITED STATES PATENT OFFICE

WALDEMAR F. MAYER, OF RUTHERFORD, NEW JERSEY, ASSIGNOR TO THE ALBA CORPORATION, OF ST. ALBANS, VERMONT, A CORPORATION OF VERMONT

SHEET FOLDER

Application filed November 24, 1928. Serial No. 321,733.

This invention relates to improvements in sheet folding machines. In particular, a sheet folding machine is provided which may be adjusted for establishing folds of various 5 predetermined widths upon articles.

One of the objects of the present invention is to simplify the folding mechanism of the folding machine set forth in my Patent No. 1,607,407 granted Nov. 16, 1926; and to enable such mechanism to be used for the formation 10 of folds of various predetermined widths.

Another object of the present invention is to provide a folding machine of that type, in 15 which conveying tapes are dispensed with within the folding machine itself.

With these and other objects in view as will appear in the course of the following specification and claims, an illustrative form 20 of the invention is set forth on the accompanying drawings, in which:

Figure 1 is a vertical longitudinal section through the machine, substantially on line 1—1 of Fig. 2.

Fig. 2 is a vertical section through the machine substantially on line 2—2 of Fig. 1.

Fig. 3 is a detail view substantially on line 3—3 of Fig. 2, showing a part of the drive connection.

The present machine is illustrated as adapted 30 to form a redoubled or four-fold of the type set forth in my Patent No. 1,607,407 and is provided with a speed mechanism as set forth in my copending application Serial No. 319,290, filed Nov. 14, 1928, to which reference 35 may be made for further description of certain details of assemblage and operation of the present apparatus.

In the drawings, the sheet to be folded, for 40 example, a blanket or the like coming from an ironing machine, is delivered by the continuously moving tapes 10 which pass over the upper guide roller 11 journaled in the folding machine standards 12. When the 45 sheet has reached the upper end of its travel, it drops from the tapes opposite the guide roller 11 and is received between the supporting roller 13 and the first folding roller 14. As shown in Fig. 2, these rollers 13 and 50 14 are formed with cores surrounded by fab-

ric gripping coverings for greater friction, these coverings being cut away or omitted opposite the center to provide space for the feeling finger 15. This feeling finger is fixed to a rock shaft 16 likewise journaled in the 55 side standards 12 of the folding machine, the shaft being provided on the exterior of one end standard with a crank arm 17.

A second folding roller is likewise journaled in the side standards 12 and is formed 60 with a fabric covering for its entire surface. It will be noted that in the illustrated form of the device, the three rollers 13, 14 and 18 are in contact in pairs. A drive chain 19 passes over sprockets on the shafts of these 65 rollers 13, 14 and 18, and over a large sprocket 20 on the main drive shaft 21 of a change speed mechanism. The drive chain 19 causes the first roller 13 and third roller 18 to turn in a counterclockwise direction, and 70 the middle or second roller 14 to turn in a clockwise direction, these rollers being caused to move at such speeds that their peripheries have substantially no relative movement and travel at the same peripheral speed as the 75 speed of movement of the tapes 10.

A suitable change speed mechanism for connecting the main shaft 21 for the folder cam with the intermittently driven shaft 22 carrying the folder cam 24 itself is illustrated, described and claimed in my copending application Ser. No. 319,290, filed Nov. 14, 1928, to which reference is made for one type of construction utilizable for the present process. Suffice it to say that power 80 is transmitted from a gear 21^a keyed to but 85 slidable along shaft 21 to an idler gear 21^b supported by a sliding carriage 21^c. This sliding carriage 21^c may be moved and held by the employment of a handle 21^d into such 90 a position that its idler gear 21^b is brought into engagement with a selected one of the nest gears 21^e mounted on a nest gear shaft 21^f carried in the housing H of the change speed mechanism. Likewise, one of the nest 95 gears 21^e is in mesh with a large gear 21^g fixed to a sleeve 21^h having a ratchet wheel 21ⁱ with a large number of fine teeth thereon. In this way the constant rotation of the shaft 21 is transmitted to produce a constant rota- 100

tion of the ratchet disk 21^r at a speed ratio determined by the selective positioning of the idler gear 21^b with respect to the nest gears 21^a in well known manner.

The gear 21^k, sleeve 21^s and ratchet wheel 21^r are fixed together, but are loosely rotatable about the intermittent shaft 22. The intermittent shaft 22 carries an eccentric plate 22^x having two dogs or pawls 22^a, 22^b pivoted thereon and adapted to be brought into engagement with the teeth of ratchet wheel 21^r by a spring 22^c located between the dogs. The upper dog 22^a in Fig. 3 carries the pin 28 for engagement with a detent arm 29. When the dogs 22^a and 22^b are free to move, the spring 22^c forces them into engagement with the ratchet wheel 21^r and thereby a driving connection is established from the constantly rotated ratchet 21^r to the eccentric plate 22^x and thus to the intermittent shaft 22, causing a rotation of this intermittent shaft until the pin 28 comes in contact with a part of the detent lever arm 29, as will be described herein-after, thus causing a detaining of the eccentric plate 22^x and a movement of the respective dogs away from engagement with the ratchet wheel 21^r; whereby the intermittent shaft 22 is brought to a standstill at a predetermined position of the cam 24, while the ratchet wheel 21^r is permitted to continue in its traveling movement. It will be noted that this is in effect a frictional clutch engagement between the constantly driven gear wheel 21^k and the intermittent shaft 22.

The intermittent shaft 22 is likewise journaled in the housing H of the change speed mechanism and has its end projecting through the side standard 12 and is provided at the other side of this standard with a bushing 23 keyed thereto. A cooperating clamp ring 25 serves in conjunction with bushing 23 to support the cam 24 in any adjusted angular position, i. e., adjusted with respect to the angularity of the beginning of the high portion of the cam with respect to the definite stopping point of the intermittent shaft 22 as a result of the cooperation of the pin 28 and the detent lever arm 29. The screws 26 clamp the cam 24 firmly in its determined position.

The rock shaft 33 carries an arm 34 operated by the link 35 connected to the finger crank lever 17 (Fig. 1): and this shaft 33 also carries the detent lever arm 29 which has a pair of lugs 30 and 31 thereon. In the position of parts shown in Fig. 1, the feeling finger 15 has been rocked clockwise by the entering sheet, resulting in the downward movement of the connecting link 35 and a clockwise movement of the detent lever arm 29, whereby initially the pin 28 was freed from the lower lug 30, whereby the eccentric plate 22^x was permitted to make a full rotation, driving the intermittent shaft 22 along with it. In the position shown

in Fig. 1, further, this eccentric plate 22^x has just completed its full rotation and the pin 28 has now been pressed again against the upper lug 31, so that the eccentric plate is now held again against further rotation. As soon as the rear end of the sheet S' has cleared the feeling finger 15, the link 35 actuated by spring 32 will move upward, and the detent lever arm 29 will make a slight counterclockwise movement so that the pin 28 will move a slight distance further concentric with the axis of shaft 22, until it bears against the lower lug 30 and the device is ready for re-starting by the entry of a new sheet to rock the feeling finger 15. The weight of the eccentric plate 22^x will hold the pin 28 and the dog carrying it against counterclockwise movement, so that the dogs are held likewise by this weight substantially out of engagement with the ratchet wheel 21^r.

A folder shaft 36 is likewise journaled in the side standards 12 of the folding machine and supports the folder levers 37 which are fixed thereto and which carry the roller 38 resting upon the periphery of the cam 24. It will be noted that while but one cam has been described and shown, such connection may easily be provided at each side of the machine by extension of the shaft 22. The upper ends of the folder levers 37 support the folder blade 39 for swinging movement in a circular arc concentric with the axis of the folder shaft 36 from a position as shown in Fig. 1, in which the folder blade is located close between the folding rollers 14 and 18, and a lower position in which it bears outward against a spring retaining finger 40 supported on a transverse bar 41 of the machine.

The machine is provided with the necessary transverse supporting members 42; and with a receiving table 43 at the outlet end.

The operation of the machine may be described as follows:

A sheet S ascending on the delivery tapes 10 passes over the guide roller 11 and hangs down into contact with the feeding roller 13, and thereby is moved into a position between the feeding roller 13 and the first folding roller 14.

It will be assumed that initially the shaft 22 is at a standstill, its wheel 22^x and pin 28 being retained by the detent lug 30; and the folding blade 39 being in the uppermost position.

The contact of the sheet S with the feeling finger 15 will cause a clockwise movement of this finger and its rock shaft 16 and crank arm 17, resulting in a downward push on the link 35 with a similar clockwise rocking of the crank lever 34, the rock shaft 33 and the detent lever 29, resulting in a movement of the detent lug 30 away from beneath the pin 28, thus releasing this pin to permit a

clockwise rotation of the wheel 22* and the shaft 22 itself along with the cam 24 under the frictional drive from the shaft 21. It will be noted that the chain 19 drives the 5 rollers 13, 14 and 18, and the shaft 21 at a constant speed: whereas the shaft 22 moves intermittently at intervals determined by the movement of the feeling finger 15.

As the result of the release and movement 10 of the cam 24, the roller 38 is at first held out by the raised portion of the cam until substantially one-quarter of the incoming sheet has passed the delivery or feeding roller 13. The cam 24 then presents a lower 15 portion of its peripheral surface to the roller 38, and the folding blade 39 is lowered into contact with the cooperating spring fingers 40, whereby a definite portion of the sheet is held, as determined by the distance from 20 the upper edge of the folding blade 39 to the front edge of the sheet which has just passed this folding blade, that is, with a proper adjustment, one-quarter of the length of the sheet is draped at the right of the 25 edge of the folding blade 39. The rollers 13 and 14 continue to feed the sheet forward at a constant speed, but this portion of the sheet is now draped in a loop in front of, i. e., at the left of, the folding blade 39, as has 30 been described in detail in my granted Patent No. 1,607,407. After a length of the sheet, equaling approximately twice the length of the portion at the right of the upper edge of the folding blade 39, has 35 passed this edge, and is draped in a loop at the left of the folding blade, the cam 24 again presents its raised portion to the guide roller 38 and the folding levers 37 now are 40 rocked upwardly again so that the folding blade 39 is brought into the position shown in Fig. 1, in which its upper edge tucks the doubly folded sheet S¹ between the folding rollers 14 and 18 which, by the frictional 45 engagement of their coverings, engage the folded sheet and deliver it onto the table 43. The lower edge of the sheet has continued to advance on the tapes 10 and finally drops therefrom; the rollers 13, 14 continuing to 50 feed the sheet at a definite speed as the central or re-double fold line is drawn forward between the rollers 14 and 18. When the rear edge of the sheet has passed the feeling finger 55 15, the latter is drawn in a counterclockwise direction under the urge of the spring 32, and the detent lever 29 again moves to the position in which the pin 28 is held by the 60 detent lug 30. It will particularly be noted that if the rear edge of the sheet has not cleared the feeling finger 15 before the cam 65 28 and its shaft 22 has made a complete rotation, the pin 28 will be received against the detent lug 31, thus holding the cam 24 in a definite position against frictional drive from the shaft 21, wherewith the folding 70 levers 37 remain in their raised position, and

the folded sheet is advanced by the folding rollers 14 and 18 onto the table 43 as before. As soon as the rear edge of the sheet has passed the feeling finger 15, the latter flies up, and the detent lever 29 moves in a clockwise direction so that the pin 28 moves from the lug 29 down onto the lug 30 by a slight further angular movement of the shaft 22. The device is now ready for the handling 75 of a further sheet: and it will be noted that by this means the device is only started by the entering edge of a sheet, and that a sheet of greater than normal width will not result in a rotation of the cam 24 by more than 360 degrees. 80

By changing the speed ratio of the drive between the shaft 21 and the shaft 22, the cam 24 is caused to move the folding levers 37 at definite intervals of time with respect to the travel of the constantly driven tapes 10, rolls 13, 14 and 18 and shaft 21. For example, if a four-fold is to be accomplished in a sheet eighty inches long, the shaft 22 will be timed to make a complete rotation when the peripheries of the rollers 13, 14 and 18 have moved by eighty inches, and an equal distance has been traversed by the tapes 10, and a corresponding distance by the chain 19. On the contrary, if a four-fold is to be made in a sheet forty inches long, the speed ratio 90 between the shaft 21 and the shaft 22 is increased so that the latter moves twice as fast as before. A method of accomplishing this has been described in my copending application, Serial No. 319,290, filed Nov. 14, 1928, 95 to which reference is made for further details of the construction and assemblage. 100

According to the present invention, therefore, the entering sheet is caused to move downward in the mechanism at the right (in Fig. 1) of a folding blade 39 until a definite length of material has been so suspended; the folding blade is then caused to move so that a further portion of the material is suspended or draped at the other side of its edge; 105 and then this edge is introduced between the folding rollers 14 and 16 which are in contact one with another and serve frictionally to receive and draw the draped sheet from the folding blade 39. The timing of this folding blade is accomplished from the constant speed drive, which feeds the sheet into its initial hanging position through an intermittent clutch which, at time intervals corresponding to the travel of the proper length 110 of the sheet, will cause the operation of the folder blade for the purposes set forth. 115

It is obvious that the invention is not limited solely to the form of execution shown, but that it may be modified in many ways within the scope of the appended claims. 120

What I claim as new and desire to secure by Letters Patent is:

1. In a folding mechanism, first, second 130

and third rolls, means to drive said rolls continuously, said second roll being in surface contact with said first and third rolls when the machine is empty, means to feed a sheet between said first and second rolls, said first and second rolls frictionally holding said sheet and determining its speed of advancement so that the sheet moves downward at a constant speed, a receiving means located beneath said first and second rolls, and devices to actuate said receiving means so that the sheet is delivered on both sides of said receiving means and to press said receiving means and the draped sheet thereon between said second and third rolls so that said rolls remove the sheet from said receiving means.

2. A folding mechanism as in claim 1, in which said devices include a cam and cam driving means, a pin carried in rotation with said cam, and a detent lever which in one position holds said pin and therewith said cam against rotation, and in a second position liberates said pin so that the cam may rotate, and means operated by the sheet to move said lever into said second position.

3. A folding mechanism as in claim 1, in which said devices include a cam and cam driving means, means operated by said cam to move said devices, driving means for said cam including an intermittent clutch and a detent to hold the cam, and devices located between said first and second rolls and operated by the front edge of the sheet to be folded when the sheet enters between said first and second rolls whereby to release said detent and cause said driving means to move said cam through said clutch.

4. In a folding mechanism, a pair of rolls having yielding gripping surfaces, one of said rolls having a portion cut away along its length, means to feed a sheet to said rolls so that the frictional engagement between the rolls and sheet will determine the speed of advancement of the sheet, a folding device to operate upon the sheet as it is fed by said rolls, driving means for said rolls and folding device, and a finger adapted to be engaged by the front edge of the sheet as it enters between said rolls, said finger being positioned in said cut away portion, and connecting devices between said finger and said folding device whereby to release the latter for operation when a sheet enters between said rolls.

5. In a folding mechanism, a feeding device and means to drive the same continuously, a folding mechanism having a folding blade, means to operate said folding blade intermittently, and a finger located between said feeding device and said blade and operated by the front edge of a sheet passing from said feeding device whereby to release said folding device for operation.

6. A folding mechanism comprising first, second and third rollers, the axes of said rolls being spaced apart horizontally, said second

and third rolls being in yielding surface contact, the axis of said third roll being below the axis of said second roll, a folder blade movable between a position close between the second and third rolls and a position beneath the first roll, a cam to move the folder blade between said positions, and means to drive said cam at a speed proportioned to the peripheral speed of said rolls, wherewith the said first roll acts to determine the speed of movement of the sheet into cooperation with said folder blade.

7. A folding mechanism as in claim 6, in which a driving mechanism is provided to move the cam, said mechanism including a clutch member, a detent to hold said cam against movement, and a device operated by the front edge of the sheet to be folded to release said detent and engage said clutch whereby to cause said driving means to rotate said cam through a full rotation, said detent engaging and stopping said cam after such full rotation.

In testimony whereof, I affix my signature.
